Fig. 15.

A technical line drawing of a curved metal component, possibly a bracket or a flange. The drawing shows a main curved shape with a vertical tab extending downwards from its left side. The tab is labeled with the number 54. The main curve is labeled with the number 56 at its top right. Along the inner curve of the main shape, there is a label 58. At the very bottom right of the main curve, there is a label 59. The drawing uses fine lines and cross-hatching to indicate the thickness and texture of the metal.

HEEL SLOTTING MACHINE

Lewis J. Bazzoni, Swampscott, and Harry D. Elliott, Beverly, Mass., assignors to United Shoe Machinery Corporation, Paterson, N. J., a corporation of New Jersey

Application May 2, 1932, Serial No. 608,714

117 Claims. (Cl. 12—42)

This invention relates to grooving or slotting machines and is illustrated as embodied in a machine for cutting in the breasts of heels grooves or slots for receiving covers applied to the heels.

5 In United States Letters Patent No. 1,691,149, granted November 13, 1928, upon application of Anthony Cocozella, there is disclosed a shoe having a Louis heel the breast of which is provided with a wide shallow groove or slot for receiving a
 10 heel breast covering flap which is split from the heel portion of the sole of a shoe and is attached to the shank portion of the sole. After the heel, the side cover of which has been applied thereto, is attached to the shoe, the flap is secured within
 15 the groove in the breast of the heel. The upper end portions of grooves of the type disclosed in the above-mentioned patent usually extend substantially from one breast edge of the heel to the other so that when the covering flaps are secured
 20 in the respective grooves, the upper portions of the flaps will merge with the edges of the shank portions of the soles of the shoes. The breasts of heels covered in this manner have a panel effect which is attractive in appearance.
 25 Instead of forming in the breasts of heels wide grooves or slots into which the entire flap may be inserted and secured, it is sometimes the practice to form in the breast of a heel a pair of narrow slots which are located adjacent to and ex-
 30 tend along the respective breast edges of the heel. In covering such heels, the marginal portions of the side covers thereof are inturned upon and secured in these narrow slots and after the partially covered heel has been attached to the shoe, the
 35 flap is secured to the portion of the breast face of the heel included between the slots and the marginal portions of the flap are tucked into the slots alongside the tucked-in marginal portions of the side cover. Such a construction is disclosed
 40 in United States Letters Patent No. 1,704,204, granted March 5, 1929, on an application filed in the name of William H. Nutt and provides a heel, the cover of which may be quickly and effectively secured thereto, having a pleasing beaded effect
 45 at its breast face.

It is an object of this invention to provide a machine which will quickly and effectively form in curved surfaces of work pieces such, for instance, as heels of shoes, cover receiving grooves or slots of the types disclosed in the above-men-
 50 tioned patents.

With the above object in view and in accordance with a feature of the invention, the illus-
 55 trated machine is provided with slot forming means and heel positioning and supporting means

relatively movable in a curved path extending heightwise and widthwise of a positioned heel to form in a curved surface of the heel a laterally curved cover receiving slot.

The illustrated machine is described with reference to its use in forming in the breasts of Louis heels cover receiving grooves or slots such as are disclosed in the patents above-mentioned.

In order to insure accuracy in forming the slots and to reduce the cost of the slot forming operation to a minimum, heels which are slotted in the illustrated machine are automatically presented to slot forming cutters, it only being necessary for the operator to place the heels in carriers which are constructed and arranged quickly to locate and to clamp the heels in the machine and which, in accordance with a feature of this invention, comprise an abutment for engaging the attaching face of a heel, a pin extending from the abutment and shaped to enter a recess in the attaching face, a bar for engaging the lip of the heel to orient the same about the pin, and a member to clamp the oriented heel against the abutment.

The machine is provided with right and left slotting units and with a turret upon which three of the above-mentioned carriers are mounted at equally spaced distances circumferentially of the turret. The turret may be temporarily stopped at every third of a revolution to enable the operator to remove a slotted heel from and to place an unslotted heel in one of the carriers which has turned to and is stopped at a heel loading station. The heels in the respective carriers are successively presented to the right and to the left slotting units which, during a period at which the turret is at rest, operate simultaneously upon heels in two of the carriers while the other carrier is positioned at the heel loading station. The cutter of one of the units is constructed and arranged to form in the breast of a heel on one of the carriers one-half of the wide slot disclosed in the above-mentioned United States Letters Patent No. 1,691,149 or to form one of the narrow slots disclosed in the above-identified United States Letters Patent No. 1,704,204, depending upon the type of work for which the machine is equipped and adjusted, and the other unit is constructed and arranged to complete the other half of the wide slot or to form a corresponding narrow slot in the other half of a heel on the other carrier.

In order that the turret may be intermittently stopped and securely held when heels in the carriers are positioned at the operating stations,

the illustrated machine, in accordance with a further feature of the invention, is provided with a turret indexing mechanism and mechanism for locking the turret against rotation, such mechanism being constrained for movement in timed relation with each of the cutter operating units so that upon completion of the slots, the turret may be released and then indexed.

In order to simplify the construction of the cutting units and to insure that there will not be any interference between the units as they operate simultaneously, it is desirable that when the heels, which are clamped in their respective carriers, are positioned at the operating stations, they should be arranged substantially in parallel relation, and that the half of the breast of each of the heels being operated upon should be located farther from the axis of rotation of the turret than the other half of the heel. With this in view and in accordance with another feature of the invention, each of the carriers is mounted for rotation relatively to the turret and, as the turret is rotated, rotates in a direction opposite to the direction of rotation of the turret and through the same number of degrees of rotation as the turret.

In order to form the above-described slots in the breasts of heels positioned in the carriers and in accordance with another feature of this invention, in the illustrated machine each of the cutters is mounted for movement in a tortuous path, such movement being effected by supporting the cutter for simultaneous swinging movement about two axes disposed at substantially right angles to each other. Each of the cutters is journaled in a cutter carrier which is pivotally secured to a bracket comprising a projecting shaft about the axis of which the bracket may be oscillated by an arm or lever. A cam roll mounted upon the cutter carrier and arranged for engagement with a cam controls the degree of rotation of the cutter carrier about the bracket as the same is oscillated about the axis of the shaft thereby to cause the cutter to move in a path similar to the heightwise curvature of the breast of the positioned heel as it moves substantially parallel to a breast edge of the heel to form in the breast a heel cover receiving slot which is substantially parallel to a breast edge of the heel.

In order effectively to move the cam roll of the cutter carrier along the sharply curved surface of the cam through which the cutter is moved in a path following the heightwise curvature of the breast of the heel to be slotted and in accordance with another feature of the invention, the illustrated machine is provided with the above-mentioned arm for moving the cutter along the lower portion of the breast of the heel, a lever constructed and arranged to move in a direction disposed at a substantial angle to the direction of movement of the arm to move the cutter along the projecting portion of the heel breast, and resilient means operable through the arm to insure that the cam roll will be yieldingly held against the cam as the lever moves the cutter along the projecting portion of the breast of the heel. The above-mentioned lever also serves to raise the cutter away from the heel after the termination of the slotting operation to permit the heel to be indexed with the turret.

In order to form wide slots such as those disclosed in the above-mentioned Cocozella Patent No. 1,691,149 by the use of a cutter having a short cutting edge and in accordance with a further feature of the invention, the illustrated machine

is provided with means for oscillating or vibrating each of the carriers at a high rate of speed, during the travel of the cutter heightwise of the heel, widthwise of the heel to widen the slot formed in the breast of the heel. Slots formed in the breasts of different sizes of heels as well as different portions of the same slot vary in width and therefore the illustrated machine in accordance with another feature of the invention is provided with mechanism for varying the degree of vibration of the carrier during movement of the cutter past the heel.

In order that each of the cutters shall form in the breasts of heels having breast edges of different radii of curvature, slots which extend substantially parallel to the breast edges of the heels, the illustrated machine, in accordance with a further feature of the invention, is provided with mechanism for varying the distance between the cutter and the axis of the shaft of the bracket which supports the cutter carrier. In the illustrated machine provision is also made to insure that the cutter follow the heightwise curvature of the breasts of heels of different sizes and styles. This is effected by providing a plurality of cams 100 of different sizes and shapes which may be interchangeably used in the machine.

Although the machine is described with reference to the slotting of Louis heels it will be understood that cover receiving slots may be formed 105 in the breasts of Cuban heels by the use of this machine. In order to equip the machine for Cuban work the cam for causing the cutter to swing relatively to its respective carrier is replaced by a cam having a substantially plane face which is 110 suitably arranged to insure that there is practically no swing of the cutter relatively to the cutter carrier during the slotting operation. Thus the illustrated machine, in accordance with another feature of the invention, is provided with 115 a rotary cutter and a heel clamp movable one past the other in a curved path the curvature of which is constrained to planes substantially parallel to the axis about which the cutter rotates.

Each of the cutter carriers may be initially adjusted lengthwise of the positioned heel upon which it is to operate in order that the cutter shaft may be disposed horizontally when the cutter is in engagement with the breast of the heel 125 and may be initially adjusted heightwise and widthwise of the heel to insure that the axis of rotation of the bracket upon which the cutter carrier is mounted will pass substantially through the center of curvature of the breast edge of the heel along which the slot is to be formed.

In the drawings,

Fig. 1 shows a front elevational view of the illustrated machine, portions of which have been broken away to show the interior construction 135 thereof.

Fig. 2 is an elevational view of the right side of the machine illustrated in Fig. 1;

Fig. 3 shows a horizontal section of the machine taken along line III—III of Fig. 2;

Fig. 4 is another horizontal sectional view of the illustrated machine taken along line IV—IV of Fig. 1.

Fig. 5 is a vertical sectional view taken along line V—V of Fig. 3 and illustrating the construction of heel carriers and turret mechanism;

Fig. 6 shows a horizontal section taken along line VI—VI of Fig. 5;

Fig. 7 is a detail view of mechanism located at the front of the machine and actuated by a trea-

die to enable the operator to position heels in the heel carriers;

Fig. 8 is a plan view illustrating portions of the cutter operating mechanism, parts of which have been broken away to show the interior construction of such mechanism;

Fig. 9 is a vertical sectional view of the machine illustrating in detail a cam and associated mechanism for operating the slot forming cutter;

Fig. 10 is a horizontal section taken along line X—X of Fig. 1;

Fig. 11 is a detail view illustrating a cutter lift cam and associated mechanism and also a cam for causing the cutter to swing forwardly and rearwardly of the machine;

Fig. 12 shows a cam through which the turret is locked when the heels are being slotted;

Fig. 13 illustrates a cutter carrier equipped with a circular cutter or saw for forming narrow heel-cover-receiving slots in the breasts of heels;

Fig. 14 is a detail view showing the relative positions of portions of the machine illustrated in Fig. 5 when the cutters are slotting the breasts of heels;

Fig. 15 shows a cam diagram illustrating the time relation of the cams which control the movement of the heel positioning and the cutter operating mechanism;

Fig. 16 is a perspective view of a Louis heel, the breast of which has the right half of a wide heel cover receiving slot formed therein;

Fig. 17 is a view similar to that shown in Fig. 16 after the wide cover-receiving slot has been formed in the breast of the heel;

Fig. 18 is a perspective view illustrating a heel having narrow heel-cover-receiving slots formed at opposite sides of its breast and extending heightwise of the heel; and

Fig. 19 is a perspective view of the rear bottom portion of a finished shoe having heels such as illustrated in Fig. 18.

The illustrated machine is constructed and arranged to form in the breasts of heels cover-receiving grooves, recesses, or slots 30 (Fig. 17) which extend over a substantial portion of the width of the breasts of heels 32 and are further described in the above-mentioned United States Letters Patent No. 1,691,149. The illustrated machine may also be used to form in the breasts of heels narrow heel-cover-receiving grooves, recesses, or slots 34 (Fig. 18), such as are disclosed in United States Letters Patent No. 1,704,204 above referred to, and in which the marginal portion of heel breast covers and the side covers of the heels may be secured.

In order to form the heel-cover-receiving slots 30, 34 the illustrated machine is provided with three heel-positioning and clamping members or heel carriers 36 which are mounted upon a turret 38 and are automatically moved in succession in a counter-clockwise direction (Fig. 3) from a heel loading station A, where a heel is positioned in each of the carriers 36, to station B where the heel is operated upon by a cutter 40 (Fig. 1) to form a part 29 (Fig. 16) of the slot 30, or by a circular cutter or saw 42 (Fig. 13) to form the right slot 34 (Fig. 18). The heel is then indexed upon the turret 38 to station C where the slot 30 is completed by another cutter 40 similar to the cutter 40 at station A, or where a slot 34 is formed at the left side of the breast of the heel by another circular cutter or saw 42.

It will be noted at this time that when forming the slots 30 the heel carriers 36 are rapidly vibrated or oscillated widthwise of the path of

movement of the cutters 40, 42 in order to form the wide slot 30 (Fig. 17) by cutters 40, each of which has short beveled cutting edges. When forming the slots 34 the carriers 36, and therefore the heels mounted thereon, are held stationary.

If heels are positioned upon successive carriers 36 at station A, after the turret has moved two-thirds of a revolution, the opposite lateral portions of two heels are simultaneously slotted by cutters 40 or 42 at stations B and C. The heels on their respective carriers 36, through mechanism which will later be described, always remain parallel to themselves as they are moved with the turret 38 upon their respective carriers 36.

The cutters 40 and 42 are constructed and arranged to move heightwise of the heels positioned breast upwards, as shown at Fig. 5, at stations B and C in a path substantially corresponding to the heightwise curvature of the breast of the heel, and, at the same time, swing in an arc following the breast edges 44 in order that the sides 46 and 48 of the slots 30 and 34, respectively, may be parallel to their respective breast edges 44, except at the projecting portions 50 of the breasts of the heels where the sides 46 and 48 are inclined to the adjacent breast edges 44, and terminate at the upper breast corners 52 of the heels. The cutter may, therefore, be defined as being mounted for movement in a tortuous path. In shoes having Louis heels (Fig. 19) the breast cover 54 is split from the rear portion of the sole 56 and is left attached to the shank portion 58 of the sole. The cover 54, which is commonly referred to as a breast covering flap, is laid upon the breast of the heel after the same has been attached to the shoe, and, in order that the lateral edges of the flap may form an uninterrupted continuation of the edges of the shank portion of the shoe it is desirable that the top portions of the slots 30 and 34 shall extend to the upper breast corners 52 of the heel.

The illustrated machine is automatic in its operation, the operator only being required to place heels in the positioning and clamping members or carriers 36 when the turret 38 is at rest, the turret rotating in a counterclockwise direction (Fig. 3) and each of the heels having its top lift attaching face 74 facing the operator. By causing the heel to remain parallel to itself as it moves from station B to station C it will be clear that the portion of the breast of the heel to be slotted is so presented to the cutters that the cutters operating in stations B and C may be conveniently mounted for swinging movement without interfering with each other.

In order to present heels to the cutters 40, 42 the illustrated machine, as above stated, is provided with the turret 38 comprising the three carriers 36 spaced at equal distances around the turret which is mounted for rotation in a horizontal plane upon a vertically disposed shaft 62 (Fig. 5) journaled in the main frame of the machine. Each of the carriers 36 includes an abutment 64 with which the attaching face of the heel 32 engages, each of the heels being provided with a recess 66 to receive a pin 70 carried by the abutment 64 and a clamp 72 which is constructed and arranged to engage the top lift attaching face 74 of the heel and may be moved away from the abutment 64 by the operator through mechanism which will later be described.

When a heel carrier 36 arrives at loading station A, the heel is properly oriented about the pin 70 by engaging the lip 68 (Figs. 17 and 18) of

80

85

145

150

the projecting portion of the heel with a stationary plate 76 which is adjustably secured through the screw-and-slot connections 78 to the main frame. In order that the lips 68 of heels of different sizes and shapes may engage the plate 76 when the recess formed in each of the heels engages the pin 70 the recess 66 is always formed at a uniform distance from the lip 68.

As the carriers 36 successively arrive at loading station A, the operator steps upon the treadle 80 (Fig. 2) which, through a rod 82 and an offset bell-crank-lever 84 (Fig. 7), operates a lug 86 secured to sliding rods 88 mounted in front and rear guide lugs 94, 96, respectively, thereby to move the clamp 72 secured to the sliding rods 88 against the pressure of springs 90 and away from the abutment 64 in order to remove a slotted heel from the machine and to insert an unslotted heel in the machine. Each of the springs 90 encircles its corresponding sliding rod 88 and has its rear end in engagement with a collar 92 (Fig. 5) which is forced against a shoulder of an enlarged portion 93 of the rod and engages at its forward end forward guide lugs 94. The springs 90, therefore, normally move the clamp 72 rearwardly until the clamp engages the heel positioned against the abutment 64, the offset bell-crank lever 84 working against the force of the springs 90 to move the clamp 72 forwardly for removing a slotted heel from the carrier and to insert another heel to be slotted in the carrier. It will be noted that an elbow portion 98 (Fig. 7) of the bell-crank-lever 84 is pivotally mounted upon a pin 100 extending at right angles to the direction of movement of each of the carriers 36 as it arrives at loading station A and is normally held upright for positioning behind the lug 86 for the purpose above described. If, however, the lug 86 and the upstanding elbow portion 98 should be out of adjustment so that the lug 86, in arriving at station A, strikes the side of the elbow portion 98, such portion will pivot about the pin 100 against the pressure of a spring 102, the lower end of which is attached to the bell-crank-lever 84 and the upper portion of which is attached to a pin 104 carried by the elbow portion 98 of the bell-crank-lever. In order to insure that the bell-crank-lever 84 and its associated treadle mechanism is moved to its rearward inoperative position, the bell-crank-lever 84 is provided with a rearwardly extending arm 106 (Fig. 2) the rear end of which is attached to a spring 108 to cause the arm 106 to engage a projection 110 of the main frame.

The turret 38 carries three shafts 112 (Fig. 5) each secured to a drum 114 which is rotatably supported upon the turret 38 by roller bearings 116 and serves as a base upon which the heel-positioning and clamping members or carriers 36 are mounted. The front and the rear guide lugs 94 and 96 respectively, are formed integral with the drum 114 and the abutment 64 is adjustably secured to the drum by a nut 118 which is in threaded relation with an extension 120 of reduced diameter at the upper end of the shaft 112.

Secured to the lower end of each of the shafts 112 is a pinion 122 which is constructed and arranged to mesh with a floating pinion 124 mounted for vertical movement upon a cylindrical bearing pin 126 pinned at 128 to the turret 38. The floating pinion 124 is normally moved downwardly against a flanged lower end 130 of the pin 126 by a spring 131 but may be moved to a position illustrated in Fig. 14 through mechanism which will soon be described.

The turret 38 is supported for rotation upon

ball bearings 132 (Fig. 5) located on top of a fixed pinion 134 arranged to mesh with the floating pinion 124 and secured to the main frame by a screw 136. The pinions 122, 124 and 134 are of equal diameter and have the same number of teeth, the arrangement being such that as the shaft 62 is rotated in a counter-clockwise direction, as seen from above (Fig. 3), through a certain arc, the shafts 112, as they travel with the turret through that arc, will rotate in a clockwise direction with respect to the turret through an equal arc. It will thus be clear that heels positioned in the carriers 36 will remain in parallel relation as the turret 38 is rotated or indexed progressively to advance the heels.

The driving mechanism for the shaft 62 is so constructed and arranged, as will later be described, that it stops for a period at every third of a revolution while a slotted heel is being removed from the machine and another is inserted therein at loading station A, the two heels positioned in the other two carriers in the meanwhile being slotted at stations B and C.

Power is supplied to the machine through a driving belt 138 (Figs. 3 and 4) which connects a motor 140 with a counter-shaft 142 extending forwardly and rearwardly of the machine. The counter-shaft 142 carries a worm 144 constructed and arranged to mesh with a gear 146 keyed to a shaft 148 (Fig. 4) and extending transversely of the machine and provided with a disk 150 and an arm 152, to the outer end of which is secured a roller 154 formed and arranged to engage a recessed disk 156 (Figs. 1 and 4) pinned to a shaft 158. Upon rotation of the shaft 148 a Geneva movement is imparted to the shaft 158, the periphery of the disk 150 serving progressively to engage slight concavities 160 formed in the periphery of the recessed disk 156 to lock the same in position while the heels are being slotted and until the disk 156 is again indexed by the rotation of the arm 152. Keyed to the shaft 158 is a bevel gear 162 which meshes with a bevel gear 164 secured to the bottom of the vertical drive shaft 62, the ratio of the gears 162 and 164 being 2:1 in order that, as the slotted disk 156 is indexed one-sixth of a revolution by the arm 152, the turret 38 will move through one-third of a revolution and come to a stop until the arm 152 again moves around and indexes the slotted disk 156.

When the carriers 36 arrive at stations A, B and C, respectively, it is desired that the turret 38 be clamped against rotative movement, since even a slight displacement thereof would result in an improperly positioned slot in the breast of the heel. Accordingly, when the heels positioned in the carriers 36 are properly located a sliding bracket 166 (Figs. 2 and 5) having at its upper portion a tapered opening 168, will engage, depending upon the position of the turret 38, one of three correspondingly shaped plungers 170 which are carried by the turret 38 in vertically extending bores 172 and are yieldably slidable therein. Each of the plungers 170 has an enlarged head 174 and an elongated shank 176, the upper portion of which is threaded to receive a plunger-retaining collar 178. Surrounding the shank 176 of each of the plungers 170 is a heavy spring 180, one end of which engages the head 174 of the plunger and the other end of which engages a shoulder of the turret 38, the arrangement being such that the plunger 170 is urged downwardly by the spring 180 until the collar 178 engages the upper surface of the turret. The

plunger 170 is, therefore, slidingly carried by the 5 turret, the projection of the plunger 170 beyond the turret being dependent upon the position of the collar 178 upon the plunger. The lower portion of the head of the plunger and the opening 168 are correspondingly tapered in order to facilitate the proper positioning of the plunger within the opening and to insure that if the plunger by mistake should extend slightly into the 10 opening 168 as the turret 38 is rotated, the plunger will be forced upwardly against the pressure of the spring 180 and will not cause injury to portions of the machine. The tapered construction of the opening 168 and the plunger 170 also permits the sliding bracket 166 to force the plunger 170 upwardly during the locking of the turret 38 thereby to insure a tight fit of the plunger 170 in the opening 168.

As above explained, it has been found that a 20 cutter 40 having a narrow beveled cutting edge will effectively form wide slots 30 in the breasts of heels when the heels are rapidly oscillated or vibrated transversely of the direction of the movement of the cutter 40 as it moves past the 25 heel in a path approximating the heightwise curvature of the breast of the heel and following a breast edge of the same. Accordingly, while the cutter is moving in such path each of the drums 114, when located at stations A and B, is vibrated 30 or oscillated about the axis of the shaft 112 by an arm 182 formed integral with the pinion 122 and carrying a depending roller 184.

Each of the rollers 184 successively engages at 35 stations B and C respectively swinging cams 186 (Figs. 2 and 3) secured to a shaft 188 positioned in a transversely extending boss 190 (Fig. 2) of the sliding bracket 166. To operate the swinging cams 186 the machine is provided with an arm 192 (Fig. 1) pinned to a shaft 194 mounted in 40 the main frame and carrying a transversely extending pin 196 for supporting a block 197 which fits into a vertically extending guideway 198 of a depending flange 200 of the right hand swinging cam 186. To the shaft 194 is keyed an up-standing arm 202 (Fig. 2) the upper end of 45 which carries a pin 204 of a suitable size to receive a hub portion of a link 206, the opposite end of which is connected to a stud 208 carried by a slide 210 which is adjustable along a guideway 50 212 of an actuating lever 214 pivotally mounted in the main frame upon a shaft 216.

In order to oscillate the shaft 216 and thereby 55 the lever 214 an arm 218 is secured to the shaft 216 and is linked to a connecting rod 220, the lower end of which is mounted upon a crank 222 (Figs. 2 and 4) carried by a shaft 224 which is rotatably supported in the main frame and to which is keyed a bevel gear 226 which meshes with another gear 228 keyed to the countershaft 60 142.

When the axis of the stud 208 carried by the slide 210 is in line with the axis of the shaft 216 upon which the lever 214 is mounted, each of the swinging cams 186 will remain stationary as the lever 214 is oscillated. It will be noted, however, 65 that as the slide 210 is raised along the guideway 212 the angle of oscillation of the arm 202, and therefore of the cam 186, will increase.

In forming slots 30 in the breasts of Louis heels 70 it is desirable that the degree of oscillatory movement of the carrier 36, when forming the upper portion of the slot 30, should be greater than when the lower portion of the slot is being formed, the difference between the degree of oscillation of the cutter at the top and the lower

portions of the heel being greatest when operating upon a full Louis heel, the width of which tapers to a considerable extent from the top to the bottom of the heel. To vary the swinging movement of the cam 186 during each slot-forming operation, the slide 210 is connected through a link 230 to an arm 232 pivoted at 234 to the main frame and pivotally connected through a link 236 to a cam follower 238 fulcrumed on a shaft 240 supported by the main frame. The cam follower 238 is urged against a swing-varying cam 242 by a spring 244, one end of which engages the rear end of the cam follower 238, and the other end of which is attached to the main frame. As the cam follower 238 rides from the lower part 246 of the swing-varying cam 242 and up the shoulder 248, the carrier 36 will begin to oscillate the degree of oscillation increasing to substantially a point 250, after which the degree of oscillation decreases until the cam follower 238 rides down a shoulder 252 and into position upon the lower part 246 of the cam. When the cam follower 238 engages the lower part 246 of the swing-varying cam 242, as illustrated in Fig. 2, the cam is in neutral position 90 and remains stationary throughout the continuous rocking movement of the lever 214. It will be understood, that the shape of the cam may be varied in accordance with the shape of the breast of the heel to be slotted.

In forming the slots 34 (Fig. 18) it is unnecessary to vibrate the heel carrier 36 as the cutter 42 moves past the heel and, accordingly, in order to set up the machine to form such slots the swing-varying cam 242 is replaced by a circular 100 cam which has a diameter of suitable size to retain the slide 210 at its lowermost position at all times thereby causing the swinging cam 186 to remain stationary throughout the slot-forming operation.

Upward movement of the bracket 166 to lock the turret 38 and to raise each of the swinging cams 186 into engagement with the rolls 184 is effected by a turret lock cam 254 (Fig. 4) which operates the bracket 166 in timed relation with the other elements through mechanism which will now be described. The bracket 166 is provided at its lower portion with a boss 256 (Fig. 2) which is pivotally connected through a link 258 to an arm 260 (Figs. 4 and 12) of a sleeve 262 115 carried upon the bearing shaft 240. The sleeve 262 has another arm 264 which carries a cam roll 266 constructed and arranged to engage a cam track 268 (Fig. 12) of the turret lock cam 254. When the cam roll 266 engages the lower 120 portion 270 of the cam track 268 the bracket 166 is lowered to permit the turret 38 to be indexed, and when the cam roll 266 engages the upper portion 272 of the cam track 268 the turret is locked.

When each of the arms 182 (Fig. 5) is oscillated by its respective swing cam 186 to increase the width of a slot 30 formed in a heel, as above described, it will be noted that since the pinion 134 is fixed, it is desirable to throw the floating pinion 124 to a raised position such as shown in Fig. 14, during the slot-forming operation. This is effected by providing the bracket 166 with a cup portion 274 which, upon upward movement of the bracket 166 to lock the turret 38, engages 130 the lower surface of the floating pinion 124 and moves the same along the cylindrical bearing pin 126 against the pressure of the spring 131. Upon the completion of the slotting cut and upon downward movement of the bracket 166 the float- 135

ing pinion 124 is moved back to its original position under pressure of the spring 131.

Each of the rotary cutters 40, 42 is secured to a shaft 276 of a motor 278 journaled in a cutter carrier 280. The cutter carrier 280 is trunnioned at 282 upon a pair of depending arms 284 which are secured to a U-shaped bracket 286 and relatively to which the cutter 40 or 42 swings under the control of a cam roll or follower 288 (Figs. 1 and 9) carried upon a shaft 289 and shaped and arranged to engage a cam 290 to cause the cutter to follow the heightwise curvature of the heel. As the cutter moves as above described it swings around an axis 292 (Fig. 1) of a vertically disposed post or shaft 294 to cause the cutter to follow the curvature of the breast edge 44 of a positioned heel.

The mechanisms for operating right and left cutters 40 or 42 are substantially identical in construction but are reversed in arrangement in order that right and left units will form the right and the left halves of the slots 30, respectively, or the right and left slots 34, respectively, according to the type of work being operated upon. In the following description reference will be made to one of the cutting units only, it being understood, however, that for each part of one unit the other has a reversed but corresponding part.

The cam roll 288, which is mounted upon the shaft 289 journaled in the cutter carrier 280, is normally urged downwardly against the cam roll 290 by a spring pressed plunger 296 slidably mounted in a rearwardly extending boss of the cutter carrier 280 and constructed and arranged to engage a lug 298 carried by the depending arm 284 of the U-shaped bracket 286. The U-shaped bracket 286 may be set in predetermined clamped relationship with respect to a horizontally disposed bracket supporting bar 300 secured by a pin 302 to the upright post or shaft 294 mounted for rotation in a vertical housing 304 (Fig. 2) and having a collar 306 secured to its upper end and serving to support the cutter-carrying mechanism 45 through a ball thrust bearing 308.

The cutter carrier 280 may be swung around the axis 292 of the post 294 by a cutter-operating lever 310 (Fig. 2) extending rearwardly of the machine and having at its forward end a recessed portion which, with a plate 312 (Fig. 1) screwed to the lever 310, forms a socket for receiving a ball portion 314 of a stud 316 bolted to the inner end of the U-shaped bracket 286.

Each of the operating levers 310 is of telescopic construction, the forward portion 318 (Fig. 2) thereof being adjustable relatively to a housing portion 320 by releasing screws 322 and, after such adjustment is effected, tightening the same. The rear end of each of the levers 310 is provided with a socket 324 (Figs. 2 and 3) shaped to receive a ball 326 carried by an arm 328 secured to a sleeve 330 (Fig. 3) which is keyed to a shaft 332 journaled in the main frame. The rear end of the socket 324 is closed by a plate 334 screwed to the rear end of the housing portion 320, the ball 326 normally being forced against the housing portion 320 of the lever 318 by a plunger 336 which is urged forwardly of the machine by a spring 338 housed in an extension 340 of the plate 334. The reason for this construction will appear presently.

To the outside end of the shaft 332 is secured an arm 342 having a lengthwise extending channel 344 and connected through a link 346 to an arm 348 keyed to a shaft 350 which is supported

by the main frame. The shaft 350 is secured at its inner end to an arm 352 (Figs. 4 and 11) which carries a roller 354 constructed and arranged to engage a closed cam track 356 of a cutter swing cam 358. Upon a complete revolution of the cam 358 the cutter 40 or 42 through the above-described mechanism is moved rearwardly and forwardly of the machine in a complete cycle.

The throw of the arm 328 may be lengthened or shortened by causing the point at which the link 346 is pivoted to the arm 342 to be adjusted along the arm. This adjustment may be conveniently effected through the provision of a dovetail block 360 mounted in a correspondingly shaped channel 344 of the arm 342 and carrying a pin 362 to which the link 346 is pivotally secured. Adjustment of the block 360 along the channel 344 is readily carried out by first releasing clamp screws 364 and then turning a hand wheel 366 which is rotatively secured to the arm 342 and in threaded relation with the block 360. When this adjustment has been made the clamp screws 364 are again tightened to retain the block 360 in adjusted position relatively to the arm 342.

In order to form the slot 30, the cutter 40 after moving from the top lift attaching face 74 to the attaching face of the heel has its direction reversed to cause it again to pass over the breast of the heel thereby to smooth out the slot. In forming the slots 34, however, there is no advantage gained by causing the cutter 42, after having formed the slot, to retrace its steps and, accordingly, the cutter 42 is moved only in one direction past the heel.

The cam 290 (Fig. 9), which controls the swing movement of each of the cutters 40, 42 about the trunnions 282, is secured to a slide 368 through a bar 370 (Fig. 10) carried by the slide 368 and having a vertically extending face constructed and arranged to engage the front face 372 of the cam 290 to aline the same properly lengthwise. The cam 290 is secured in position against the bar 370 by a clamp 374 carried by the slide 368 and having a wedge portion 376 adapted to engage a V-shaped recess 378 in the rear face of the cam. It will be clear that as a screw 380, through which the clamp 374 is secured to the slide 368, is tightened, the clamp will force the cam 290 against the bar 370 and retain the same in a predetermined adjustment therewith. Through the above mechanism the cam 290 may be readily replaced by a cam of a different shape when the operator desires to slot heels, the breasts of which have a heightwise curvature different from that of the heels being slotted.

The slide 368 at its under side is provided with a dovetail recess 382 (Fig. 9) for receiving a correspondingly shaped projection 384 of a plate 386 supported upon a horizontally projecting flange 388 (Figs. 5 and 9) of the main frame and adjustable forwardly and rearwardly of the machine along a dovetail tongue 390 (Fig. 1) by turning a screw 392 which is rotatably mounted with respect to the flange 388 and is in threaded relation with a depending lug 394 (Fig. 10) secured to the plate 386. In order to lock the plate 386 against movement and to release the same for adjustment along the tongue 390, the plate 386 comprises a spline portion 391 which engages one side of the tongue 390 and which may be forced against the tongue by a wedge arm 397, one end of which engages a recess in the spline portion 387 and the other end of which is shaped to engage a tapered end of a screw 399 carried by the plate 386. The cam 290

may thus be conveniently adjusted forwardly and rearwardly of the machine by turning the screw 392 and may be adjusted widthwise of the machine by moving the slide 368 relatively to the plate 386, after loosening lock screws 396 in threaded relation with the slide 368 and serving frictionally to bind the slide with the plate 386.

It will be noted that the steep portion 398 of the cam 290, along which the cam roll 288 moves to guide its corresponding cutter along the projecting portion of the breast of the heel positioned in the carrier 38, is inclined at a steep angle to the direction of movement of the cutter operating lever 310. Accordingly, the machine is provided with lifting levers 400 (Figs. 1, 2 and 3) each carrying at its forward end a screw 402 which engages the under side of a projecting lug 404 of the cutter carrier 280 and assists the cutter operating arm 310 in moving the cam rolls 288 up the steep portion 298 of the cam 290. Each of the cutter lifting levers 400 is adjustably mounted lengthwise of itself by means of a screw-and-slot connection 406 (Fig. 2) along a guideway 408 of an arm 410 secured to a shaft 412 mounted in the main frame. The shaft 412 is keyed to a rearwardly extending arm 414 (Figs. 2 and 3) the rear end of which is pivotally attached to a rod 416. In order to actuate the rod 416, the machine is provided with a cutter lifting cam 418 (Figs. 4 and 11) which engages a cam roll 420 secured to one end of an angle arm 422 supported for oscillation upon the shaft 240. The other end of the angle arm 422 is pivotally connected to the rod 416, the cam roll 420 being held in engagement with the cutter lifting cam 418 through a spring 424 one end of which is secured to the angle arm 422 and the other end of which is secured to the main frame.

In order to regulate the time at which the lifting lever 400 is effective, the screw 402 carried by the lever 400 may be adjusted relatively to the lever 400, the operation of the lever being so timed that when the cam roll 288, which is moved rearwardly of the cutter operating lever 310, reaches the curved portion 398 of the cam 290, the lifting lever 310 will raise its respective cutter carrier 280 to cause the cutter 40 or 42 to swing upwardly about the trunnions 282 thereby to assist the cam roll 288 in climbing the curved portion 398 of the cam 290.

As already stated, it is customary to run each of the cutters 40 and 42 back over the breast of the heel and thus to smooth out the bottom of the slot 30. Whether or not it is desirable to have each of the cutters 40 retrace its path, depends to a considerable extent upon the ratio of the rate of vibrations of the carrier 36 during the slot forming operation to the speed of the cutter heightwise of the heel. In practice it has been found that satisfactory results have been obtained by decreasing somewhat the ratio of the rate of vibratory movement of the carrier 26 to the rate of speed of the cutter heightwise of the heel and by causing the cutter again to move heightwise of the slotted heel, but in a reverse direction back to its original starting position. Accordingly, after each of the cutters 40, 42 has been raised above the lip 68 of the projecting portion of the heel, the lifting lever 400 is temporarily stopped during about 20° of rotation of the cutter lifting cam 418. The lifting lever 400 is then gradually lowered and the cam roll 288 in the meantime under the force of gravity moves down the portion 398 of the cam 290 to

move the cutter forwardly of the machine and down the projecting portion 50 of the breast of the heel.

It is desirable that the cam roll 288 shall be held tightly but with a yielding pressure against the curved portion 398 of the cam 290. This is effected through the above-described connection between the cutter operating lever 310 and the arm 328, the ball 326 carried by the arm 328 during the first part of the slot forming operation being held against the forward portion of the rear socket 324 by the spring 338. As the cam roll 288 moves up the sharply curved portion 398 of the cam 290, the arm 328 travels faster than the cutter operating lever 310 which is slowed up by contact of the cam roll 288 with the sharply curved portion 398 and this causes the ball 326 to compress the spring 338 as the cutter lifting lever moves the cam roll 288 up the steep portion 298 of the cam.

As each of the cutters moves forwardly and beyond the top lift attaching face 74 of the heel the lever 400 is lifted through the above-described mechanism and raises with it one of the cutters 40, 42 which swings about the trunnions 100 282 in order that the heel positioned in the following carrier 36 may be indexed into proper position upon the turret 48 preparatory to starting another slotting operation. When the turret 38 has been indexed and the heels next to be 105 operated upon are again located at stations B and C, respectively, each of the cutter lifting levers 400 is lowered to permit the cutter which is normally urged downwardly by the spring-pressed plunger 296 to be lowered until the cam roll 288 110 engages the forward end portion 426 (Fig. 9) of the cam, it being noted that the cam is of considerable length in order that after the cutter has moved past the top lift attaching face 74 of the highest type of heel, the cam roll will rest upon the end portion 426 of the cam 290 to position the cutter as the lifting lever 400 is lowered to ineffective position. The machine is thus ready to move each of the cutters 40, 42 rearwardly of the machine to start the slotting operation.

It will be understood that the cutters may be controlled so that they move heightwise of the heel in one direction only preferably from the top lift receiving face 74 to the attaching 125 face of the heel. Such an arrangement is especially useful in forming the narrow slots 34 by the use of the circular cutters 42. Accordingly, as the cutter 42 passes beyond the lip 68 of the projecting portion 50 of the heel after having 130 moved from one end of the heel to the other, the cutter lifting lever 310 is raised to move the cutter above and out of the way of the heel. When slotting heels as above described, as the cutter is moved away from the heel, the turret 38 is 135 unlocked and is then indexed to position the next heel to be slotted relatively to the cutter. As the turret 36 is being indexed, the cutter operating lever 310 moves the cutter 42 forwardly of the machine, and, after the heel has been indexed, the lifting lever 400 is lowered to permit the cam roll 288 to engage the portion 426 of the cam 290, thus positioning the cutter 42 just ahead of the top lift receiving face of the heel 74 and ready to move rearwardly through the 140 above-described mechanism to form a slot 34 in the newly-presented heel.

The abutment 64 (Fig. 5) may be adjusted relatively to the drum 114 in order that when slots 30 are being formed in the breasts of heels hav- 150

ing varying transverse convexities at their projecting portions, the distance between the axis 428 of the shaft 112 and the heel engaging face of the abutment may be varied. It is customary 5 to set the abutment 62 so that the distance 430 is approximately equal to the transverse radius of curvature of the projecting portion of the breast of the heel, in order that as the heel is 10 oscillated about the axis 428, the depth of material removed from different transverse portions 15 of the breast of the heel will be substantially the same to insure that the bottom of the slot 30 at the projecting portion of the breast will have approximately the same curvature as the corresponding original portion of the breast of 20 the heel. When the above adjustment has been made, it will be clear that the cutter and its operating and guiding instrumentalities will also have to be changed by mechanism which will 25 presently be described.

As above stated, when the style of the heels to be slotted is changed, it is generally desirable to change the radius of swing of the cutter about the axis 292 of the post 294 as well as to replace the cam 290 by a cam having a cam roll engaging surface of a different curvature from that of the cam removed. To effect the adjustment of the cutter in relation to the axis 292, the machine is provided with a trough-shaped member 432 (Fig. 1) which is positioned in an extension of the slide 368 through the forwardly and rearwardly extending dovetail end guideway connection 434, shaped to receive the depending stud 316 carried by the U-shaped bracket 286. When 30 the stud 316 is positioned within the trough-shaped member 432, screws, which are carried by the U-shaped bracket 286 and normally serve to clamp the bracket to the bar 300, are released and the bar 300 is adjusted along the U-shaped 35 bracket 286 until the axis 292 of the post 294 has been properly located relatively to the cutter.

In order initially to locate the cutter relatively to the positioned heel after the adjustment just described has been made, the U-shaped bracket 45 286 and the bar 300 are adjustable as a unit widthwise, heightwise and longitudinally of the machine by mechanism which will now be described. The vertical housing 304 is provided with a laterally extending flange 438 having in 50 its rear face a vertically disposed dovetail recess 440 (Fig. 8) constructed and arranged to engage a correspondingly shaped tongue of a vertically extending plate 444. The housing 304 may be raised or lowered by a hand screw 446 which is in threaded relation with an extension 448 (Fig. 55 2) of the housing 304 and having its lower end in engagement with the upper face of the plate 444. In order to carry out this adjustment, set screws 450 carried by the flanges 438 of the housing 304 are released and the hand screw 446 is turned to raise or to lower the cutter. After the proper adjustment has been effected, the set screws 450 are again tightened to retain these 60 parts in adjusted position with respect to each other.

The cutter may be adjusted widthwise of the machine without disturbing the distance between the cutter and the axis 292. Such an adjustment is made when it is desired to form heel cover receiving slots in the breasts of heels, the width of 65 which is different from the width of the heels which the machine has been operating upon. In order to make this adjustment, each of the plates 444 has in its rear face a horizontally disposed dovetail channel 452 (Fig. 2) constructed and ar-

ranged to receive a tongue 454 formed at the forward end of a bed plate 456. In order to effect the adjustment of the plate 444 along the tongue 454, the machine is provided with screws 458 which are in threaded relation with the wedge clamps 459. When the screws 458 are released, a hand screw 460 rotatably mounted on the tongue 454 and in threaded relation with a lug 462 secured to the plate 44 is turned until the cutter is properly positioned, after which the clamp screws 458 are tightened to maintain the plate 444 in adjusted position.

When it is desired to slot heels having the same general heightwise curvatures as heels for which the machine is adjusted and having wider breasts, the operator, after placing the trough-shaped member 432 on the slide 368, releases the screws 396 (Fig. 1) and also the screws 436 and turns the hand screws 460. Accordingly, as the cutter carrier 280 moves widthwise, the cutter cam 290, which is mounted upon the slide 368, also partakes of the adjustment. After the proper adjustment has been effected, the screws 436 are again tightened and the trough-shaped member 432 is removed from the machine.

In order to align the axis of rotation 292 (Fig. 1) with the center of curvature of the side of the heel adjacent to the breast edge thereof, the plate 444 may be moved longitudinally of the machine by adjusting the bed plate 456 forwardly or rearwardly of the machine. Such adjustment is performed by releasing clamp screws 464 and by turning a hand screw 466, one end of which is rotatably mounted in the sliding bed plate 456 and the other end of which is in threaded relation with a lug 468 secured to the main frame. When the desired adjustment has been made, the screws 464 are again tightened to clamp these parts together.

In order to cut the cam roll engaging surface 115 of the cam 290 to a shape adapted to control the cutter in a path similar to that of the heightwise curvature of the breast of the heel, the cams 290 may be cut by using as a template a heel having the desired heightwise curvature. With this in 120 view, the machine is provided with a pinion 470 (Fig. 1) which may be temporarily placed upon the rear projecting end of the cutter shaft 276 and meshes with another pinion 472 placed upon the cam shaft 289. A roller is then mounted upon the shaft 276 but is not held for positive rotation therewith and a cutter is secured to the shaft 289 in place of a cam roll 283. As the cutter operating lever causes the cam cutter to move in a heightwise path controlled by the roll which is in engagement with the breast of the heel, the cam cutter forms in the cam block a surface corresponding in shape to the breast of such heel.

It is desirable in making adjustments on the machine to turn over the operating parts slowly. Accordingly, the machine is provided with a hand crank 474 normally urged forwardly of the machine by a spring 476 and having at its rearward end a serrated portion 478 constructed and arranged to engage a corresponding serrated portion 480 mounted upon the forward end of the counter shaft 142.

The operation of the machine will now be described. Assuming that the main driving motor 140 and the motors 278 which operate the cutters 40 and 42 have been started; as one of the carriers 36 arrives and is stopped at position A (Fig. 3), the operator steps on the treadle 30 to move the clamp 72 forwardly of the machine and away from the abutment 64. After the heel has been 145 150

placed in the machine in a position such as illustrated in Fig. 5, the treadle 80 is then released in order to permit the clamp 72 firmly to press the heel against the abutment 64. The turret 38, 5 after a predetermined period, is automatically indexed through the above-described mechanism to move the heel positioned in the carrier 36 to position B. As the heel is moved with the carrier 36, it remains parallel to itself; the carriage 36, 10 as it arrives at station B, being locked.

In the cam diagram illustrated in Fig. 15 reference numerals 482, 484, 486, and 488 graphically represent the displacement of the turret lock cam 254, the cutter swing cam 358, the cutter lift cam 418, and the cutter swing varying cam 242, respectively, during a complete cycle of the machine. By reference to this diagram, the timing relationship between the cams will be clear, it being understood that such diagram is 15 for the purpose of illustrating one condition of operation of the machine and that the timing and the shape of the cams depends upon the type of heels being slotted and upon the type of slot to be formed.

25 The cams are illustrated as starting at 0° which corresponds to the time that the cutter is at its forwardmost point of travel. As the cams are rotated from 0° to 10°, the cutter does not move forwardly or rearwardly of the machine 30 and the turret lock cam 482 raises the sliding bracket 166 to lock the turret 38, the cutter lift cam 486 in the meanwhile causing each of the lifting levers 400 to be lowered thereby to permit the cutter carrier 280 also to be lowered 35 until the cam roll 288 engages the forward portion 426 (Fig. 9) of the cam 290. During the first 10° of rotation of the cams, the cutter swing varying cam 242 causes the slide 210 to remain at the lower end of the guideway 212 of the 40 actuating lever 214 to hold the swinging arms 186, which through the above-described mechanism oscillate the carriers 36, stationary.

From approximately 10° to 135° of rotation of the cams, the cutter is moved rearwardly of the 45 machine, the heightwise pivotal movement of the same about the trunnion 282 being controlled by the cam 290, and the cutter carrier 280 being swung about the axis 292 of the post 294. During this corresponding period, the sliding bracket 50 166, which has been raised by the turret lock cam 254, is held stationary and the cutter lifting cam 418 is designed to retain the lever 400 at its lowermost inoperative position away from the cutter carrier 280. From 10° to 25°, however, the 55 carrier swing varying cam 242 rapidly raises the slide 210 of the actuating lever 214 to cause the swinging cams 186, which respectively engage the depending rollers 184, to vibrate the carriers 36 about their respective axes 428 (Fig. 5), the 60 degree of vibration of the carriers rapidly increasing. The cutter starts to operate upon the heel when cams have been rotated through approximately 25° and at this time and until the swing varying cam has rotated to 155° the slide 210 is 65 raised gradually to increase the degree of vibration of the carriers.

As the cutter swing cam 358 rotates from 135° to 145°, it moves the arm 328 (Fig. 2) at approximately the same rate of speed as it is moved from 70 10° to 135°. During this period the cutter lift cam 418 causes the lever 400 to raise the cam roll 288 up the sharply curved portion 398 (Fig. 9) of the cam 290, this movement taking place as the cutter arrives approximately at a point 490 75 (Fig. 5) along the breast of the heel.

Because of the steepness of the portion 398 of the cam 290, the cutter, during this period, does not move so fast as it would normally move if the arm 328 were rigidly connected to the operating lever 310. As above described, the arm 328 is permitted to yield relatively to the operating lever 310 through the provision of the spring 338 and its associated elements as shown in Fig. 2. This spring is compressed by the arm 328 as the cam roll 288 moves up the portion 398 of the cam and serves to insure that the cam roll 288 is always in engagement with the steep portion 398 as it is raised by the lifting lever 400. During this period, the turret remains locked. 80 Upon rotation of the cutter swing cam 358 from 145° to 165° the arm 328 and the lifting lever 400 are at rest, the cam roll 288 being held by the tension of the spring 338 against the top part of the steep portion 398 of the cam 290 and the lever 400 serving to support the trimming mechanism in its raised position. The turret in the meantime remains locked, and the degree of swing of the carriers 36 which reaches a maximum at 155° starts to decrease gradually until the cam 242 has rotated through 290° which corresponds to the time when the cutter moves forwardly of the top-lift receiving face 74 of the heel. 85 90 95 100 During the rotation of the cutter swing cam 358 from 165° to 175°, the cutter operating lever 310 is pulled forwardly of the machine under force of gravity by the carrier 280 and its associated parts as the lever 400 is lowered, the cam roll 288 being held tightly against the steep portion 398 of the cam by the spring 338 which is 105 held by the ball 326 of the arm 328 until the cutter reaches the point 490 on the breast of the heel. The ball 326 carried by the arm 328 in the meanwhile has been traveling forwardly of the machine faster than the cam roll 288 and 110 when the cutter reaches the point 290, the ball 326 engages with the forward part of the socket 324 for positively moving the cam roll 288 forwardly of the machine. 115 120 125 During the rotation of the cams from 175° to 305°, the cutter is moved from point 490 on the breast of a heel forwardly of the top lift receiving face 74 of the heel, the turret continuing to remain locked and the cutter lift cam 418 retaining the lifting lever 400 in its lowered inoperative position. The cutter swing-varying cam 242 during its rotation from 155° to approximately 290°, as above explained, gradually lowers the slide 210 in the actuating lever 214, thereby causing the degree of swing of the carriers 36 gradually to 130 decrease and after rotating through 290°, which corresponds to the time that the cutter moves off the breast of the heel, the swing of the carriers rapidly diminishes until the cam 242 has rotated through 305°. 135 140 145 When the cutter swing cam 358 has rotated through 305°, the cutter has completed the slotting operation and has moved forwardly of the top-lift receiving face 74 of the heel and upon continued rotation of this cam to 360° no forward or rearward movement is imparted to the cutter. As the carrier swing-varying cam 242 rotates from 305° to 360° the slide 212 remains in its lowered position in order that there will be no vibration of the carrier during this period. From 305° to 315°, however, the slide bracket 166 is moved downwardly until the turret 38 is free to be indexed, this cam during a period from 315° to 360° being constructed to retain the slide bracket 166 in a lowered position during which 150

period the turret is indexed. In order to move the cutter away from the turret 38 the cutter lift cam 418, as it rotates from 305° to 315°, raises the cutter above the turret and during its continued rotation to 360° retains the cutter in such raised position.

It will again be noted that as the bracket 166 is lowered, the cup portion 274 thereof permits the floating pinion 124 to be moved to its lowered position illustrated in Fig. 14 in order that as the turret 38 is indexed, the heel in the carrier will remain parallel to itself. While the operation of the machine has been described with reference to one of the carriers 36, it will be understood that the machine is constructed and arranged to operate simultaneously upon a heel positioned in each of the carriers located at stations A and B, a side of the breast of one heel being slotted at station A and the other side 20 of the breast of the other heel being slotted at station B. By providing the turret with a third carriage 36, which, while the other two heels on the turret are being slotted, is positioned at loading station A, the operator is able to remove 25 a heel which has already been slotted in the machine and to replace it with an unslotted heel during the slot forming operation.

It will be understood that the above-described operation has been included for the purpose of 30 illustrating the invention, and that instead of having the cutters 40, 42 move twice over the breast of the heel, the timing and the design of the cams may be such that when the cutter has moved from the top-lift receiving face 74 to the 35 attaching face of the heel, it may be lifted away from the control of the cam 290 and therefore away from the heel instead of retracing its heightwise path of movement to the top-lift receiving face of the heel 74. Such an operation 40 may be advantageously used when forming the slots 34, since the character of the slot is not improved by moving the cutter back along the narrow slot 34. Moreover, by moving the cutter away from the heel when it arrives at the lip 68 of the 45 projecting portion of the heel, the turret 38 may then be indexed as the heel is held in raised position by the lever 400 and is being moved back to its starting position by the cutter operating lever 310.

Having described our invention, what we claim 50 as new and desire to secure by Letters Patent of the United States is:

1. A slotting machine having, in combination, slot forming means and heel positioning and 55 supporting means relatively movable in a curved path extending heightwise and widthwise of a positioned heel to form in a curved surface of the heel a laterally curved cover receiving slot.

2. In a machine of the class described, slot forming means and a heel support constructed 60 and arranged for relative movement in a tortuous path to form in the curved breast of a heel upon the support a laterally curved cover receiving slot.

3. A slotting machine having, in combination, slot forming means and a heel support constructed and arranged for relative movement in a tortuous path to form in the breast of a Louis heel upon the support a laterally curved heel cover receiving slot which is substantially parallel to one 65 of the breast edges of the heel.

4. A slotting machine having, in combination, a support for a Louis heel, a slot-forming cutter, and means for moving the cutter in a curved path following the general heightwise curvature 70 of the breast of the heel and curved widthwise

of the heel thereby to form a heel cover receiving slot in the breast of the heel.

5. A slotting machine having, in combination, a support for a Louis heel, a slot-forming cutter, and means including a cam to control the cutter 80 in a curved path following the general heightwise curvature of the breast of a Louis heel and curved laterally of the heel thereby to form a tortuous heel cover receiving slot in the breast of the heel.

6. A slotting machine having, in combination, a support for a Louis heel, a slot forming cutter, and means for moving the cutter relatively to the support in a tortuous path thereby to form in the breast of the heel mounted upon the support 85 a heel cover receiving slot curved widthwise of the breast of the heel.

7. A slotting machine having, in combination, a member to support and to position a Louis heel, and a cutter constructed and arranged for movement relatively to the member in a tortuous path 95 following the general heightwise curvature of the heel and extending substantially parallel to one of the breast edges of the heel.

8. A slotting machine having, in combination, a support for a heel, and a cutter mounted for 100 bodily swinging movement about two axes disposed at substantial angles to each other and constructed and arranged to form in a curved surface of a heel upon the support a laterally curved heel cover receiving slot.

9. A slotting machine having, in combination, means constructed and arranged to position and to support a Louis heel, a slot-forming cutter, and means bodily to swing the cutter about two axes disposed at substantially right angles to each other thereby to form in the breast of the heel a cover 110 receiving slot which extends heightwise of the heel and is curved laterally.

10. A slotting machine having, in combination, a support constructed and arranged to position 115 and to clamp a heel, and a rotary cutter mounted for bodily swinging movement about two axes disposed at substantial angles to each other thereby to form in the breast of the heel on the support a heel cover receiving slot which is curved widthwise of the breast of the heel.

11. A slotting machine having, in combination, a cutter, a support for a work piece, means for causing relative progressive movement of the support and the cutter thereby to form a slot in the 125 work piece, and means for causing relative reciprocation of the support and the cutter widthwise of the slot during said progressive movement thereby to increase the width of the slot.

12. A slotting machine having, in combination, 130 a cutter, a support constructed and arranged to position a heel and to clamp the same in position, means for causing relative progressive movement of the work support and the cutter to form a cover receiving slot in the heel, and means for causing relative reciprocation of the work support and the cutter widthwise of the slot in the heel during said progressive movement thereby to increase the width of the slot.

13. A groove-forming machine having, in combination, a support mounted for reciprocation and constructed and arranged to position a work piece, a cutter mounted for movement in a predetermined path relatively to the support, and means simultaneously to reciprocate the support and 140 to move the cutter past the support to form in the work piece a wide groove.

14. A slot-forming machine having, in combination, a support mounted for reciprocation and constructed and arranged to position and to clamp 145

- a heel, a cutter mounted for movement in a predetermined path relatively to the support, and means simultaneously to reciprocate the support and to move the cutter past the support to form in the heel a wide slot for receiving the cover of the heel. 15. A groove-forming machine having, in combination, a rotary cutter mounted for movement in a predetermined path, a support constructed and arranged to position a work piece and mounted for vibratory movement transversely of said path, and means to vibrate the support and to move the cutter along said path to form in the work piece and elongated groove the width of which is determined by the degree of vibratory movement of the work support. 16. In a slotting machine, a support constructed and arranged for oscillation, a rotary cutter mounted for movement in a predetermined path relatively to the work support, and means to oscillate the work support as the cutter moves in said path to form in a work piece mounted upon the support a slot for receiving a cover applied to the work piece. 17. A slotting machine having, in combination, a support constructed and arranged to position a wood heel and mounted for oscillatory movement, a cutter movable in a path corresponding substantially to the curvature of a surface of a heel, means to move the cutter in said path, and means to oscillate the support during movement of the cutter in said path in order to form upon the heel a slot to receive a heel cover. 18. A slotting machine having, in combination, a support constructed and arranged to position and to clamp a wood heel and mounted for oscillatory movement, a rotary cutter movable in a predetermined path, means to move the cutter in said path, and means to oscillate the support during movement of the cutter in said path at an angle to said path to form in the heel mounted upon the support a slot for receiving a heel cover. 19. A slotting machine having, in combination, slot forming means and heel supporting means relatively movable progressively in a curved path to form in a curved surface of a heel upon said support a curved heel cover receiving slot, and means for causing relative oscillation of the slot forming means and the heel supporting means in paths extending widthwise of said slot thereby to widen the slot during said relative movement in the curved path. 20. A slotting machine having, in combination, slot forming means and heel supporting means relatively movable in a curved path to form in a curved surface of a heel upon said support a curved heel cover receiving slot, said slot forming means and said heel supporting means being mounted for relative reciprocation transversely of said path to widen the slot during said relative movement in the curved path, and means constructed and arranged to vary the degree of reciprocation in order to change the width of the slot. 21. A slotting machine having, in combination, slot forming means and heel supporting means relatively movable in a curved path to form in a curved surface of a heel upon said supporting means a curved heel cover receiving slot, said slot forming means and said heel supporting means being mounted for relative reciprocation transversely of said path to widen the slot during said relative movement in the curved path, and means constructed and arranged to vary the degree of reciprocation during said relative movement in said curved path thereby to vary the width of different portions of the slot. 22. A slotting machine having, in combination, slot forming means and a heel support constructed and arranged for relative movement in a tortuous path to form in the breast of a Louis heel upon the support a heel cover receiving slot which is substantially parallel to one of the breast edges of the heel, and means to cause relative vibratory movement of the slot forming means and said support in paths disposed widthwise of the heel thereby to widen the slot during said relative movement along the path. 23. A slotting machine having, in combination, a support for a heel, a cutter constructed and arranged for progressive movement relatively to the support in a tortuous path to form in the breast of a heel upon the support a heel cover receiving slot curved widthwise, and means to vibrate the support relatively to the cutter in a path extending transversely of said path thereby to widen the slot formed in the breast of the heel by said cutter as it is moved along said path. 24. A slotting machine having, in combination, a support for a heel and a cutter constructed and arranged for movement relatively to the support in a tortuous path to form in the breast of the heel upon the support a heel cover receiving slot curved transversely of the breast of the heel, said cutter and said support being mounted for relative oscillation transversely of said path to widen the slot formed by the cutter as it moves in said path, and means constructed and arranged to vary the degree of oscillation during said relative movement in the path thereby to vary the width of the slot along different portions thereof. 25. A slotting machine having, in combination, a support for a Louis heel, a cutter constructed and arranged for progressive movement relatively to the support in a tortuous path extending generally heightwise of the heel positioned in the support thereby to form in the breast of the heel a heel cover receiving slot arranged parallel to a breast edge of the heel, and means to vibrate the support relatively to the cutter widthwise of the heel during the movement of said cutter thereby to widen the slot. 26. A slotting machine having, in combination, a support for a Louis heel, a cutter constructed and arranged for movement relatively to the support in a tortuous path extending generally heightwise of the heel positioned in the support to form in the breast of the heel a cover receiving slot extending parallel to a breast edge of the heel, said support being mounted for oscillation transversely of said path during movement of said cutter to widen the slot formed thereby, and means constructed and arranged to vary the degree of reciprocation of the support during movement of the cutter thereby to vary the width of the slot formed in the heel along different portions of the same. 27. A slotting machine having, in combination, a support for a heel, a cutter constructed and arranged for bodily swinging movement about two axes disposed at substantial angles to each other to form in a curved surface of a heel upon the support a laterally curved heel cover receiving slot, and means to vibrate the support transversely of the path of movement of said cutter thereby to widen the slot formed in the heel as the cutter is moved in said path. 28. A slotting machine having, in combination, a support for a heel and a cutter constructed and arranged for movement about two axes disposed

- at substantial angles to each other to form in the breast of a Louis heel upon the support a heel cover receiving slot which is curved widthwise of the breast of the heel, said support being mounted for oscillation widthwise of said path of movement to widen the slot formed by the cutter, and means constructed and arranged to vary the degree of oscillation of the support thereby to vary the width of the slot. 80
- 10 29. A slot forming machine having, in combination, a support mounted for oscillation and constructed and arranged to position a work piece, a cutter mounted for movement in a predetermined path relatively to the support, and means simultaneously to move the cutter past the support and to oscillate the support through an arc across said path to form in the work piece a wide slot. 85
- 15 30. A slot forming machine having, in combination, a rotary cutter mounted for movement in a predetermined path, a support constructed and arranged to position a heel and mounted for vibratory movement in an arcuate path disposed transversely of the path of movement of the cutter, and means to vibrate the support and to move the cutter along said path to form in the heel an elongated cover receiving slot the width of which is controlled by the degree of vibratory movement of the work support. 90
- 20 31. A slotting machine having, in combination, slot forming means and heel supporting means relatively movable in a curved path to form in a curved surface of a heel upon the support a heel cover receiving slot, and means to cause relative vibratory movement of the slot-forming means and said heel-supporting means in arcuate paths extending transversely of said first-named path thereby to widen the slot during the above said relative movement. 95
- 25 32. A slotting machine having, in combination, a support for a Louis heel, a cutter constructed and arranged for movement relatively to the support in a tortuous path extending generally heightwise of the heel positioned in the support, and means to vibrate the support in a circular path having a radius of curvature equal substantially to the radius of curvature of a transverse portion of the upper projecting part of the breast of the heel during said movement of the cutter thereby to widen the slot. 100
- 30 33. A slotting machine having, in combination, a support for a Louis heel, a cutter constructed and arranged for movement relatively to the support in a tortuous path extending generally heightwise of the heel positioned in the support to form in the breast of the heel a cover receiving slot extending parallel to a breast edge of the heel, and means to vibrate the support in a circular path having a radius of curvature substantially equal to that of the curvature of a transverse portion of the upper projecting part of the breast of the heel thereby to widen the slot formed by the cutter. 105
- 35 34. A slotting machine having, in combination, a support for a Louis heel, a rotary cutter constructed and arranged for movement relatively to the support in a tortuous path extending generally heightwise of the heel positioned in the support to form in the breast of the heel a cover receiving slot extending parallel to a breast edge of the heel, said support being mounted for vibratory movement in a circular path having a radius of curvature substantially equal to that of a transverse portion of the upper projecting part of the breast of the heel to widen the slot 110
- 40 formed by the cutter, and means constructed and arranged to vary the degree of vibration of the support during movement of the cutter thereby to vary the width of the slot formed in the heel along different portions thereof. 80
- 45 35. A slotting machine having, in combination, slot forming means, and means to position a heel the breast of which has a projecting portion, said slot forming means and said heel positioning means being mounted for relative movement to form in the projecting portion of the breast of the heel a heel cover receiving slot which extends heightwise of the heel and terminates at one of the upper breast corners of the heel. 85
- 50 36. A grooving machine having, in combination, a rotary cutter, and means constructed and arranged to position a heel the breast of which has a projecting portion relatively to the cutter, said cutter and said heel positioning means being mounted for relative movement to form in the projecting portion of the breast of the heel a heel cover receiving groove inclined toward one of the breast edges of the heel. 90
- 55 37. A heel slotting machine having, in combination, a support for a heel, a rotary cutter, said cutter being mounted for swinging movement about two axes disposed at substantially right angles to each other to form in the breast of the heel upon the support a heel cover receiving slot extending heightwise and widthwise of the heel. 100
- 60 38. A slotting machine having, in combination, a support for a Louis heel, a rotary cutter, said cutter being mounted for swinging movement about two axes disposed at substantially right angles to the axis of rotation of the cutter and at substantially right angles to each other, means to move the cutter about one of said axes, and a cam shaped and arranged to control the movement of the cutter about the other axis as the cutter moves about said one axis thereby to form in the breast of the heel upon the support a heel cover receiving slot extending heightwise and widthwise of the heel. 110
- 65 39. A slotting machine having, in combination, a support for a heel, a rotary cutter, said cutter being mounted for swinging movement about two axes disposed at substantially right angles to the axis of rotation of the cutter and at substantially right angles to each other, means to move the cutter about one of said axes, a cam shaped and arranged to control the movement of the cutter about the other axis as it moves about said one axis to form in the breast of the heel upon the support a heel cover receiving slot extending heightwise and widthwise of the heel, and means to vary the distance between the cutter and said one axis to vary the lateral radius of curvature of the slot. 120
- 70 40. A slotting machine having, in combination, a support constructed and arranged to position a heel, a cutter mounted for swinging movement about two axes disposed at substantial angles to each other, means to swing the cutter about one axis, and a cam to control the movement of the cutter about the other axis as the cutter swings about said one axis to cause the cutter to form in the heel a heel cover receiving slot. 135
- 75 41. A slotting machine having, in combination, a support constructed and arranged to clamp a Louis heel, a cutter mounted for swinging movement about two axes disposed at substantially right angles to each other, means to swing the cutter about one axis, and a cam to control the movement of the cutter about the other axis as 145

- the cutter swings about said one axis to cause the cutter to form in the breast of the heel a heel cover receiving slot extending substantially parallel to a breast edge of the heel.

5 42. In a slotting machine, a rotary cutter, a turret, a carrier mounted upon the turret and constructed and arranged to position a heel, means to rotate the turret to move the carrier from a position in which the heel may be inserted 10 in the carrier to a position in which the heel may be presented to the cutter, and means to swing the cutter past the heel presented thereto about an axis in a path the plane of which is disposed at substantially right angles to said axis thereby 15 to form a cover receiving slot in the heel.

43. In a slotting machine, a cutter, a turret, a carrier mounted upon the turret and constructed and arranged to position a heel, means to rotate the turret to move the carrier from a position in 20 which the heel is inserted in the carrier to a position in which the heel is presented to the cutter, mechanism to cause the carrier to remain parallel to itself during rotation of the turret, and means to move the cutter past the 25 heel presented thereto to form therein a heel cover receiving slot.

44. In a slotting machine, a turret, a cutter, a carrier mounted on the turret and constructed and arranged to position a heel, means to index 30 the turret to move the carrier from a heel loading position to a position in which the heel is presented to the cutter, and means to move the cutter past the heel so presented to form therein a heel cover receiving slot.

35 45. In a slotting machine, a turret, a rotary cutter, a carrier mounted upon the turret and constructed and arranged to position a Louis heel, means to index the turret to move the carrier from a heel loading position to a position in 40 which the heel is presented to the cutter, and means to move the cutter in a curved path past the heel to form in the breast thereof a heel cover receiving slot.

46. In a slotting machine, a turret, a cutter, a carrier mounted upon the turret and constructed and arranged to position a heel, means to index 45 the turret to move the same from a heel loading position to a position in which the heel is presented to the cutter, and means to swing the cutter about two axes disposed at substantial angles 50 to form in the breast of the heel a heel cover receiving slot extending heightwise and widthwise of the breast of the heel.

47. In a slotting machine, a turret, a rotary cutter, a carrier mounted upon the turret and constructed and arranged to position a Louis heel, means to index the turret to move the same from a heel loading position to a position in which the heel is presented to the cutter, and means to 55 swing the cutter about two axes disposed at substantially right angles to the axis of rotation of the cutter and at substantially right angles to each other to form in the breast of the heel a heel cover receiving slot which is substantially 60 parallel to a breast edge of the heel.

48. A heel slotting machine having, in combination, a turret mounted for rotation, a plurality of carriers each of which is movable with the turret and is constructed and arranged to 65 position a work piece, means to rotate the turret successively to move the carriers from a work loading position to a position in which the work piece may be operated upon, mechanism to lock the turret against rotation when the carrier is 70 in the last-named position, and means construct- 75 ed and arranged to vibrate the carrier relatively to the turret while in said last-named position.

49. In a heel slotting machine, a cutter mounted for movement, a turret, a carrier mounted upon the turret and constructed and arranged to position a work piece upon the same, means to index the turret to move the carrier in position to permit a heel carried thereby to be operated upon by the cutter, and means constructed and arranged to vibrate the carrier relatively to the 80 turret while in said position.

50. In a machine for operating upon shoes, a cutter, a turret mounted for rotation, a carrier movable with the turret and constructed and arranged to position a work piece upon the same, means to index the turret to present the work piece to the cutter, members constructed and arranged to rotate the carrier relatively to the turret during the indexing movement of the same in a direction opposite to the direction of movement 85 of the turret and through an arc which is equal to the arc of movement of the turret, mechanism to lock the turret against rotation when the heel is in position to be operated upon, and means constructed and arranged to vibrate the carrier relatively to the turret while in said indexed position.

51. In a machine for operating upon shoes, a turret mounted for rotation, a carrier mounted upon the turret and constructed and arranged to position a shoe part, and means constructed and arranged to rotate the carrier relatively to the 90 turret during rotation of the same in a direction opposite to the direction of movement of the turret and through an arc which is equal to the arc of movement of the turret thereby to cause the carrier to remain parallel to itself as it moves with the turret.

52. In a slotting machine, a turret mounted for rotation, a carrier movable with the turret and constructed and arranged to position a work piece, means to index the turret, members to rotate the carrier in a direction opposite to the direction of rotation of the turret as the same is being indexed, mechanism to lock the turret against rotation when the same has been indexed, 95 means constructed and arranged to vibrate the carrier relatively to the turret while in said indexed position, and means to render said members inoperative in order to permit oscillation of the carriage relatively to the turret when the same is locked.

53. A machine for operating upon shoes having, in combination, a turret, means to rotate the turret, a plurality of carriers each of which is mounted upon the turret and is constructed and arranged to position work to be operated upon, means to index the turret simultaneously to position one of the carriers in a work loading position while another of the carriers is located in a position in which work clamped in that carrier may be operated upon, mechanism to rotate each of the carriers relatively to the turret during 100 said indexing movement of the same, a lock to prevent rotation of the turret when one of the carriers is in said last-named position, and means constructed and arranged to vibrate the carrier relatively to the turret while in said last-named position.

54. A heel-slotting machine having, in combination, a pair of rotary cutters each of which is mounted for swinging movement about two axes disposed at substantial angles to each other, a support to position a pair of heels relatively to the respective cutters, means simultaneously to operate the cutters thereby to form a cover re- 105

ceiving slot in the breast of each of the heels, and means for moving the support to present the heels successively to the cutters.

55. A slotting machine having, in combination, 5 a support for a heel, a rotary cutter, said cutter being mounted for swinging movement about two axes disposed at substantially right angles to the axis of rotation of the cutter and at substantially right angles to each other, means to move the 10 cutter about one of said axes, a cam shaped and arranged to control movement of the cutter about the other axis as the cutter moves about said one axis to form in the breast of the heel a heel cover receiving slot extending heightwise and 15 widthwise of the heel, and means to move the cutter away from the heel to render said cam inoperative in controlling the movement of the cutter after its slot forming operation and while it is moved back to its initial position.

56. In a slotting machine, a support constructed and arranged to clamp a Louis heel, a cutter mounted for swinging movement about two axes disposed at substantially right angles to each other, means to swing the cutter about one axis,

25 a cam to control the movement of the cutter about the other axis as the same swings about said one axis to cause the cutter to form in the breast of the heel a heel cover receiving slot extending substantially parallel to a breast edge 30 of the heel, and an arm constructed and arranged to raise the cutter from the work and to hold the same away from the work after the slot has been formed and until the cutter is moved to its starting position preparatory to forming a slot in another heel.

57. A slotting machine having, in combination, a support constructed and arranged to clamp a heel, a cutter mounted for swinging movement about two axes disposed at substantially right angles to each other, means to swing the cutter about one axis and a cam to control the movement of the cutter about the other axis as the same swings about said one axis thereby to cause the cutter to form in the breast of the heel a heel cover receiving slot extending parallel to a breast edge of the heel, and mechanism to vary the distance between said axes thereby to change the curvature of the path of movement of the cutter in order that the cutter may form in the breasts of heels the breast edges of which are of different radii of curvature heel cover receiving slots which are substantially parallel to the breast edges of the respective heels.

58. In a slotting machine, a turret, a cutter, a carrier mounted upon the turret and constructed and arranged to position a heel, means to index the turret to move the same from a heel loading position to a position in which the heel is presented to the cutter, means to swing the cutter about two axes disposed at substantial angles to form in the breast of the heel a heel cover receiving slot extending heightwise and widthwise of the breast of the heel, and mechanism to vary the distance between said axes to change the path of movement of the cutter.

59. In a slotting machine a turret, a rotary cutter, a carrier mounted upon the turret and constructed and arranged to position a Louis heel, means to index the turret to move the same from heel loading position to a position in which the heel is presented to the cutter, means to swing the cutter about two axes disposed at substantially right angles to each other to form in the breast of a heel a heel cover receiving slot

which is substantially parallel to a breast edge of the heel, and means to vary the distance between said axes to vary the path of movement of the cutter to form in heels the breast edges of which are of different radii of curvature heel cover receiving slots which are substantially parallel with said breast edges.

60. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, means to move the cutter in a predetermined path past the work pieces to form a cover receiving slot in said work piece, mechanism to lock the turret against rotation when the carrier is in the last-named position, and means to vibrate the carriers while in said position relatively to the turret to widen said slot upon movement of the cutter past the work piece in said path.

61. In a slot forming machine, a cutter, a turret, 100 a carrier mounted upon the turret and constructed and arranged to position a work piece upon the same, means to index the turret to position a work piece to be operated upon by the cutter, means to move the cutter in a predetermined path past the work piece, an arm attached to the carrier, and a cam constructed and arranged to oscillate said arm to impart a vibratory movement to the carrier relatively to the turret.

62. In a slotting machine, a cutter, a turret 110 mounted for rotation, a carrier movable with the turret and constructed and arranged to position a work piece upon the same, means to index the turret to move the work piece to a position to be operated upon by the cutter, means to move the 115 cutter in a predetermined path past the work piece to form a slot therein, members to rotate the carrier in a direction opposite to that of the turret as the same is being indexed, mechanism to lock the turret against rotation when the heel 120 is in position to be operated upon by the cutter, and a cam to impart vibratory movement to the carrier when the turret is locked.

63. A heel-slitting machine having, in combination, a pair of cutters, heel-carrying members 125 a pair of which are constructed and arranged to be positioned adjacent to the respective cutters, means to position a heel on each of the members, cutter carriers mounted for movement relatively to the respective members, means to oscillate the 130 members which are positioned adjacent to the cutters, means to control the movement of the cutter carriers relatively to the members as the same are oscillated thereby to cause the cutters simultaneously to form in the breasts of the respective heels cover receiving slots one edge of each of which is parallel to a corresponding portion of one of the breast edges of the respective heel, and means successively to present each of the members to the cutters.

64. A heel slotting machine having, in combination, means to position a heel, a member mounted for oscillation, a cutter, a cutter carrier supported by and mounted for oscillation relatively to said member, means to oscillate the member, and 145 means to control the oscillation of the carrier relatively to the member as the same is oscillated thereby to cause the cutter to form a heel cover receiving slot in the heel mounted upon said means, and mechanism for imparting to the heel 150

- positioning means a vibratory movement in a direction disposed at substantially right angles to the path of movement of the cutter in order to widen the slot so formed.
- 5 65. A heel slotting machine having, in combination, means to position a heel, a member mounted for oscillation, a cutter, a cutter carrier supported by and mounted for oscillation relatively to the member, means to oscillate the member, a cam to control the oscillation of the carrier relatively to the member as the same is oscillated to cause the cutter to form in a heel upon said means a heel cover receiving slot, and means to lift the cutter away from the work.
- 10 66. A heel slotting machine having, in combination, means to position a heel, a member mounted for oscillation, a cutter, a cutter carrier movable with and mounted for oscillation relatively to the member, means to oscillate the member, a cam to control the oscillation of the carrier relatively to the member as the same is oscillated to cause the cutter to form a heel breast receiving slot in the heel upon said means, mechanism constructed and arranged to urge the cutter against the cam during the heel slotting operation, and a lift constructed and arranged to raise the carrier away from the cam at the end of the heel slotting operation.
- 15 67. A heel slotting machine having, in combination, mechanism to position a heel, a member mounted for movement about an axis, a cutter, a cutter carrier mounted for movement about said axis and also about an axis disposed at a substantial angle to said axis, a cam, said cutter carrier comprising a cam roll constructed and arranged to engage said cam, and resilient means to force the cam roll against said cam to cause the cutter to move in a predetermined path as it is oscillated about said first-named axis to form in the breast of the heel mounted upon said mechanism a heel cover receiving slot, said member and said carrier being relatively adjustable to vary the radius of curvature of the cutter about said first-named axis.
- 20 68. In a slotting machine, a turret, a heel carrier mounted for rotation with the turret and constructed and arranged to clamp a heel, mechanism to cause a heel clamped in the heel carrier to remain parallel to itself upon rotation of the turret, a pair of cutters, means to present the heel successively to the cutters, means to move one of the cutters to form in the breast of the heel a heel cover receiving slot which is parallel with one breast edge of the heel when the heel is presented to one of the cutters, and means to move the other cutter to form in the breast of the heel when the heel is presented to such cutter a cover receiving slot which is parallel with the other breast edge of the heel.
- 25 69. In a slotting machine, a turret, a heel carrier mounted for rotation with the turret and constructed and arranged to clamp a heel, mechanism to cause the heel clamped in the heel carrier to remain parallel with itself upon rotation of the turret, a pair of cutters, means to present the heel successively to the cutters, means to move one of the cutters to form in the breast of the heel a heel cover receiving slot which is parallel with one breast edge of the heel when the heel is presented to one of the cutters, means to move the other cutter to form in the breast of the heel a heel cover receiving slot which is parallel with the other breast edge of the heel when the heel is presented to the other cutter, and means to oscillate the carrier rapidly when the heel is
- 30 70. A slotting machine having, in combination, a cutter, mechanism to present a heel to the cutter, means to move the cutter in a predetermined path over the breast of the heel to form a heel cover receiving slot in said breast, means to raise the cutter away from the heel when the slot has been formed, and means to adjust the cutter heightwise and widthwise of the breast of the heel so presented in order properly to locate the cutter to start the slot according to the shape and size of the heel which is to be slotted.
- 35 71. In a machine of the class described, a turret mounted for rotation, a carrier mounted upon the turret and constructed and arranged to position a shoe part, and mechanism to rotate the carrier relatively to the turret in a direction opposite to the direction of rotation of the turret as the turret is rotated, through an arc equal to the arc of rotation of the turret thereby to cause the carrier to face in the same direction as it is rotated with the turret.
- 40 72. In a machine of the class described, a turret mounted for rotation, a carrier mounted upon the turret and constructed and arranged to position a shoe part, a stationary gear, and a plurality of gears carried by the turret and constructed and arranged upon rotation of the turret positively to swing the carrier through an arc equal and opposite to the arc of swing of the turret upon rotation of the same in order to cause the carrier to remain parallel to itself as it rotates with the turret.
- 45 73. In a machine of the class described, a turret mounted for rotation, a carrier mounted upon the turret and constructed and arranged to position a shoe part, a stationary gear, a plurality of gears carried by the turret and constructed and arranged upon rotation of the turret positively to swing the carrier through an arc equal and opposite to the arc of swing of the turret upon rotation of the same in order to cause the carrier to remain parallel to itself as it rotates with the turret, means to lock the turret against rotation, and a member constructed and arranged to move one of the gears carried by the turret out of mesh with the other when the turret is locked.
- 50 74. In a machine of the class described, a turret mounted for rotation, a plurality of carriers mounted upon the turret, each of the carriers being constructed and arranged to position and to clamp a shoe part, a stationary gear, and a plurality of gears carried by the turret and constructed and arranged upon rotation of the turret positively to move each of the carriers through an arc equal and opposite to the arc of rotation of the turret in order to cause each of the carriers to remain parallel to itself as it moves with the turret.
- 55 75. In a machine of the class described, a turret mounted for rotation, a plurality of carriers mounted upon the turret, each of the carriers being constructed and arranged to position and to clamp a shoe part, a stationary gear, a plurality of gears carried by the turret and constructed and arranged upon rotation of the turret positively to move each of the carriers through an arc equal and opposite to the arc of rotation of the turret in order to cause each of the carriers to remain parallel to itself as it moves with the turret, means to lock the turret, means to throw the gears for controlling rotation of each of the carriers relatively to the turret

- out of mesh in order to permit each of the carriers to be moved when the turret is locked, and means for moving the carriers independently of the turret.
5. 76. In a slotting machine, a cutter, a turret mounted for rotation, a carrier movable with the turret and constructed and arranged to position a work piece thereon, means to index the turret to present the work piece in position to be operated upon by the cutter, and members to rotate the carrier upon rotation of the turret through an arc equal and opposite to the arc of rotation of the turret to cause the work piece on the carrier to remain parallel to itself during rotation past the heel to form a heel cover receiving slot in the heel, and means for vibrating the heel positioning means in a path extending across the general path of movement of the cutter. 80
10. 76. In a slotting machine, a cutter, a turret mounted for rotation, a carrier movable with the turret and constructed and arranged to position a work piece thereon, means to index the turret to present the work piece in position to be operated upon by the cutter, and members to rotate the carrier upon rotation of the turret through an arc equal and opposite to the arc of rotation of the turret to cause the work piece on the carrier to remain parallel to itself during rotation 85
15. 76. In a slotting machine having, in combination, a cutter, mechanism to present a heel to the cutter, means to swing the cutter about an axis to form a heel cover receiving slot in the breast 90
20. 76. In a slotting machine having, in combination, a cutter, mechanism to present a heel to the cutter, means to swing the cutter about an axis to form a heel cover receiving slot in the breast of the heel, and means to move the axis of rotation heightwise of the breast of the heel so positioned 95
25. 76. In a slotting machine having, in combination, a cutter, mechanism to present a heel to the cutter, means to swing the cutter about an axis to form a heel cover receiving slot in the breast of the heel, and means to move the axis of rotation heightwise of the breast of the heel so positioned in order to cause the axis of rotation of the cutter to pass substantially through the center of curvature of the breast edge of the heel to insure that the heel cover receiving slot will be substantially parallel to the breast edge of the heel. 100
30. 76. A heel slotting machine having, in combination, a support for a heel, a cutter constructed and arranged to move in a path extending heightwise of the breast of the heel in one direction and to retrace its path in an opposite direction, and means rapidly to oscillate the support across said path during movement 105
35. 76. A heel slotting machine having, in combination, a support for a heel, a cutter constructed and arranged to move in a path extending heightwise of the breast of the heel in one direction and to retrace its path in an opposite direction, and means rapidly to oscillate the support across said path during movement 110
39. 76. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, and means to move the cutter in a predetermined path past the work piece in one direction and then to move the cutter in an opposite direction along said path to form a heel cover receiving slot in said work piece. 115
40. 76. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, and means to move the cutter in a predetermined path past the work piece in one direction and then to move the cutter in an opposite direction along said path to form a heel cover receiving slot in said work piece. 120
45. 76. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, and means to move the cutter in a predetermined path past the work piece in one direction and then to move the cutter in an opposite direction along said path to form a heel cover receiving slot in said work piece. 125
50. 76. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, and means to move the cutter in a predetermined path past the work piece in one direction and then to move the cutter in an opposite direction along said path to form a heel cover receiving slot in said work piece. 130
55. 76. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, and means to move the cutter in a predetermined path past the work piece in one direction and then to move the cutter in an opposite direction along said path to form a heel cover receiving slot in said work piece. 135
60. 76. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, and means to move the cutter in a predetermined path past the work piece, mechanism to lock the turret against rotation when the carrier is in the last-named position, and means to vibrate the carriers while in said position relatively to the turret to widen said slot upon movement of the cutter past the work piece. 140
65. 76. A heel slotting machine having, in combination, a cutter, a turret mounted for rotation, a plurality of carriers each of which is movable with the turret and is constructed and arranged to position a work piece, means to rotate the turret successively to move the carriers from a work loading position to a position in which the work piece may be operated upon by the cutter, and means to move the cutter in a predetermined path past the work piece, mechanism to lock the turret against rotation when the carrier is in the last-named position, and means to vibrate the carriers while in said position relatively to the turret to widen said slot upon movement of the cutter past the work piece. 145
70. 81. A heel slotting machine having, in combination, means to position a heel, a member mounted for oscillation, a cutter, a cutter carrier supported by and mounted for oscillation relatively to said member, means to oscillate the member, and means to control the oscillation of the carrier relatively to the member as the same is oscillated to cause the cutter to move first in one direction and then in an opposite direction 150
75. 81. A heel slotting machine having, in combination, means to position a heel, a member mounted for oscillation, a cutter, a cutter carrier supported by and mounted for oscillation relatively to said member, means to oscillate the member, and means to control the oscillation of the carrier relatively to the member as the same is oscillated to cause the cutter to move first in one direction and then in an opposite direction past the heel to form a heel cover receiving slot in the heel, and means for vibrating the heel positioning means in a path extending across the general path of movement of the cutter. 155
82. A machine of the class described having, in combination, a turret, a carrier mounted upon the turret, a stationary gear, and a plurality of planetary gears mounted for rotation in the turret and constructed and arranged upon rotation of the turret to rotate the carrier in a direction opposite to the direction of rotation of the turret. 80
83. A machine of the class described having, in combination, a turret, a carrier mounted for movement with and for rotation relatively to the turret, a stationary gear concentrically mounted relatively to the axis of the turret, a gear secured to the carrier, and another gear mounted for rotation with the turret and constructed and arranged to serve as a driving connection between the stationary gear and the gear connected to the carrier. 85
84. A machine of the class described having, in combination, a turret, a carrier mounted for movement with and for rotation relatively to the turret, a stationary gear concentrically mounted relatively to the axis of the turret, a gear secured to the carrier, and another gear mounted for rotation with the turret and constructed and arranged to serve as a driving connection between the stationary gear and the gear connected to the carrier, said gears having the same number of teeth in order to rotate the carrier as it is rotated with the turret through an arc equal to the arc through which the turret is rotated and in an opposite direction to the direction of rotation of the turret thereby to insure that the carrier will remain parallel with itself as it moves with the turret. 90
85. A machine of the class described having, in combination, a turret, a carrier mounted for movement with and for rotation relatively to the turret, a stationary gear, a gear secured to the carrier, and another gear mounted for rotation with the turret and constructed and arranged to serve as a driving connection between the stationary gear and the gear connected to the carrier, said last-named gear being constructed and arranged to be moved out of mesh with the other said gears to permit the carrier to be rotated when the turret is stopped. 95
86. A slotting machine having, in combination, a support to position and to clamp a Louis heel, a cutter movable heightwise of the breast of the heel, said support being mounted for oscillation about an axis passing substantially through the center of curvature of a transverse portion of the upper projecting part of the breast of the heel, and means simultaneously to operate the cutter and to oscillate the support to form in the breast of the heel a heel cover receiving recess the bottom of which has the general shape of the unrecessed projecting portion of the breast of the heel. 100
87. A slotting machine having, in combination, a member constructed and arranged to support and to position a Louis heel, and a cutter mounted for movement heightwise of the heel, said member being mounted for oscillation about an axis passing substantially through the center of curvature of an arc extending transversely of the breast of the heel at the upper projecting portion of said breast. 105
88. A slotting machine having, in combination, a support to position and to clamp a Louis heel, said support comprising an abutment to engage 110

- the attaching face of the heel and comprising a pin positioned for insertion in a recess formed in said face of the heel, a bar to orient the heel relatively to the abutment, a clamp to force the heel against said abutment to hold the heel in position against the same, a cutter mounted for movement along the breast of the heel, said support being mounted for oscillation about an axis passing substantially through the center of curvature of an arc extending transversely of the breast of the heel at the upper projecting portion of said breast, and means simultaneously to operate the cutter and to oscillate the support thereby to form in the breast of the heel a heel cover receiving slot extending over a substantial portion of the breast of the heel. 80
- 10 89. A slotting machine having, in combination, a support for a Louis heel, a cutter movable in a path corresponding substantially to the heightwise curvature of the breast of the heel, and means constructed and arranged to oscillate the support about an axis extending lengthwise of the heel and positioned beyond the attaching face of the heel. 90
- 15 90. A slotting machine having, in combination, a support for a Louis heel, said support having a surface constructed and arranged to engage the attaching face of the heel, a cutter movable in a path corresponding to the heightwise curvature of the heel, an axis about which the support is oscillated, said axis lying substantially in the vertical median plane of the positioned heel and extending substantially parallel with said surface of the support, and means simultaneously to oscillate the support and to move the cutter past the heel thereby to form in the breast thereof a cover receiving recess. 95
- 20 91. In a slotting machine, a member constructed and arranged to support and to position a Louis heel, and a cutter mounted for movement heightwise of the heel, said member being mounted for oscillation about an axis passing substantially through the center of curvature of an arc extending transversely of the breast of the heel at the upper projecting portion of the breast of the heel, said member and the axis about which the member is oscillated being relatively adjustable. 100
- 25 92. A recessing machine having, in combination, a support to position and to clamp a Louis heel, a cutter movable in a curved path corresponding to the heightwise curvature of the breast of the heel, said support being mounted for oscillation about an axis passing substantially through the center of curvature of a transverse portion of the upper projecting part of the breast of the heel, means simultaneously to operate the cutter and to oscillate the support to form in the breast of the heel a heel cover receiving recess. 105
- 30 93. A slotting machine having, in combination, a support to position and to clamp a Louis heel, said support comprising an abutment constructed and arranged to engage the attaching face of the heel and having a pin positioned for insertion in an opening formed in said face of the heel, a bar to orient the heel relatively to the abutment, a spring-pressed clamp to force the heel against said abutment to hold the heel in position against the same, a cutter mounted for movement along the breast of the heel, said support being mounted for oscillation about an axis passing substantially through the center of curvature of an arc extending transversely of the breast of the heel in the upper projecting portion of said breast, means constructed and arranged to adjust the support relatively to said axis according to the transverse curvature of the breast of the heel, and means simultaneously to operate the cutter and to oscillate the support to form in the breast of the heel a heel cover receiving slot extending over a substantial portion of the breast of the heel. 110
- 35 94. A slotting machine having, in combination, a turret, a member carried by the turret and constructed and arranged to support and to position a Louis heel, and a cutter mounted for movement heightwise of the heel, said member being mounted for oscillation relatively to the turret about an axis passing substantially through the center of curvature of a transverse portion of the upper projecting part of the breast of the heel. 115
- 40 95. A slotting machine having, in combination, a support for a Louis heel, a turret constructed and arranged to carry the support, indexing mechanism to move the heel from a position in which the heel may be placed in the support to a position in which the heel may be operated upon, a cutter movable in a path corresponding to the heightwise curvature of the heel, an axis about which the support is oscillated, said pivot passing substantially through the center of curvature of a transverse portion of the upper projecting part of the breast of the heel, and means simultaneously to oscillate the support and to move the cutter past the heel to form in the breast thereof a cover receiving slot. 120
- 45 96. In a slotting machine, a turret, a drum mounted upon the turret, heel engaging members mounted upon the drum and constructed and arranged to position a Louis heel, a cutter movable lengthwise of the heel, operating mechanism to swing the drum relatively to the turret, and means to operate the cutter as the drum is oscillated to form in the breast of the heel a cover receiving slot, said heel engaging members being mounted for adjustment relatively to the drum to vary the radius through which the positioned heel is swung during the slotting operation. 125
- 50 97. A slotting machine having, in combination, a turret, a drum mounted upon the turret, heel engaging members mounted upon the drum and constructed and arranged to position and clamp a Louis heel, indexing mechanism for the turret constructed and arranged to move the drum from a position in which the heel may be placed in the heel engaging members to a position in which the heel may be operated upon, mechanism for rotating the drum through an arc equal and opposite to that through which the turret is rotated during the indexing of the same, a cutter mounted for movement heightwise of the heel located in operating position, and means simultaneously to move the cutter and to vibrate the drum, said heel engaging members being mounted for adjustment relatively to the drum to vary the radius through which they are swung. 130
- 55 98. A machine for operating upon Louis heels having, in combination, a member for positioning a Louis heel, a cutter, an arm constructed and arranged positively to move the cutter heightwise of the heel along the lower portion of the breast thereof to form a heel cover receiving slot in said breast, and another arm positively to move the cutter along the projecting portion of the breast of the heel to form a continuation. 135
- 60 75 99. A slotting machine having, in combination, a support to position and to clamp a Louis heel, said support comprising an abutment constructed and arranged to engage the attaching face of the heel and having a pin positioned for insertion in an opening formed in said face of the heel, a bar to orient the heel relatively to the abutment, a spring-pressed clamp to force the heel against said abutment to hold the heel in position against the same, a cutter mounted for movement along the breast of the heel, said support being mounted for oscillation about an axis passing substantially through the center of curvature of an arc extending transversely of the breast of the heel in the upper projecting portion of said breast, means constructed and arranged to adjust the support relatively to said axis according to the transverse curvature of the breast of the heel, and means simultaneously to operate the cutter and to oscillate the support to form in the breast of the heel a heel cover receiving slot extending over a substantial portion of the breast of the heel. 140
- 70 100. A slotting machine having, in combination, a support to position and to clamp a Louis heel, said support comprising an abutment constructed and arranged to engage the attaching face of the heel and having a pin positioned for insertion in an opening formed in said face of the heel, a bar to orient the heel relatively to the abutment, a spring-pressed clamp to force the heel against said abutment to hold the heel in position against the same, a cutter mounted for movement along the breast of the heel, said support being mounted for oscillation about an axis passing substantially through the center of curvature of an arc extending transversely of the breast of the heel in the upper projecting portion of said breast, means constructed and arranged to adjust the support relatively to said axis according to the transverse curvature of the breast of the heel, and means simultaneously to operate the cutter and to oscillate the support to form in the breast of the heel a heel cover receiving slot extending over a substantial portion of the breast of the heel. 145

of the slot in said portion, said first-named arm being constructed and arranged to insure that the cutter will move in a path following the curvature of the projecting portion of the cutter as the cutter is positively moved by the second-named arm.

99. A slotting machine having, in combination, mechanism to clamp and to position a Louis heel, a cutter, a cam to control the cutter in a path following the heightwise curvature of the breast of the heel to form in said breast a heel cover receiving slot extending heightwise of the heel, an arm constructed and arranged to move the cutter guided by the cam along the lower portion of the breast of the heel, another arm constructed and arranged to move the cutter along the projecting portion of the heel breast, and resilient means operable through the first-named arm to insure that the cam controls the path of movement of the cutter as the second-named arm moves the cutter along a projecting portion of the breast of the heel.

100. A slotting machine having, in combination, means to position a Louis heel and to clamp the same in position, a cutter, a cam, a cam roll constructed and arranged to engage the cam and to control the path of movement of the cutter heightwise of the heel to form a heel cover receiving slot in the breast of the heel, and arms constructed and arranged for movement at substantial angles to each other to move the cam roll along different portions of the cam, one of said arms being constructed and arranged yieldingly to urge the cam roll into engagement with the cam as the other arm moves the cam roll along the cam.

101. A slotting machine having, in combination, means constructed and arranged to position and to clamp a Louis heel, a rotary cutter, a sharply curved cam, a cam follower to control the cutter to form a heel cover receiving slot in the sharply curved portion of the breast of the heel, an arm to move the follower along the cam, and resilient means constructed and arranged to urge the cam follower against the cam during the operation of said arm thereby to insure that the cam follower will move in a path parallel to the cam.

102. A heel slotting machine having, in combination, means to position a heel, a member mounted for oscillation, a cutter, a cutter carrier supported by and mounted for oscillation relatively to said member, means to oscillate the member, and means to control the oscillation of the cutter carrier relatively to the member as the same is oscillated thereby to cause the cutter to form a heel cover receiving slot in a heel mounted upon said means.

103. A heel slotting machine having, in combination, means to position a heel, a member mounted for oscillation, a cutter, a cutter carrier mounted for oscillation relatively to the member, means to oscillate the member, and a cam to control the oscillation of the carrier relatively to the member as the same is oscillated thereby to cause the cutter to form a heel breast receiving slot in the heel upon said means.

104. A heel slotting machine having, in combination, means to position a heel, a member mounted for oscillation, a cutter, a cutter carrier mounted for oscillation relatively to the member, means to oscillate the member, a cam to control the oscillation of the carrier with reference to the member as the same is oscillated thereby to cause the cutter to form a heel breast receiving slot in a heel upon said means, and mechanism con-

structed and arranged to urge the carrier against the cam during the heel slotting operation.

105. A heel slotting machine having, in combination, mechanism to position a heel, a member mounted for movement about an axis, a cutter, a cutter carrier movable with said member and mounted for movement about an axis disposed at a substantial angle to said axis, a cam, said cutter carrier comprising a cam roll constructed and arranged to engage said cam, and resilient means to force the cam roll against said cam thereby to cause the cutter to move in a predetermined path as it is oscillated about said first-named axis to form in the breast of the heel mounted upon said mechanism a heel cover receiving slot.

106. In a heel slotting machine, a pair of cutters, and mechanism constructed and arranged to present a heel successively to the cutters, means to move one of said cutters to form in the breast of the heel a cover receiving slot extending parallel to one breast edge of the heel, and means to move the other cutter to form in the breast of the heel a cover receiving slot extending parallel with the other breast edge of the heel.

107. A slotting machine having, in combination, a turret, a pair of cutters, three carriers each of which is mounted upon the turret and is constructed and arranged to position a heel, means to index the turret simultaneously to position two of the carriers adjacent to their respective cutters in order that the heels carried by the carriers may be presented to their respective cutters and so to position the other carrier that a heel may be removed therefrom and another heel inserted therein, and mechanism simultaneously to move the cutters to form in the breast of each of the other two heels a cover receiving slot.

108. A slotting machine having, in combination, a turret, a pair of cutters, three carriers each of which is mounted upon the turret and is constructed and arranged to position a heel; and means to index the turret simultaneously to position two of the carriers adjacent to their respective cutters in order that the heel carried by each of the carriers may be presented to its respective cutter and so to present the other carrier that a heel may be removed therefrom and another heel inserted therein, each of said cutters being mounted for movement in a tortuous path to form in the breast of the heel positioned adjacent thereto a heel cover receiving slot extending parallel to a breast edge of the heel.

109. A slotting machine having, in combination, a cutter, mechanism to present a heel to the cutter, means to move the cutter in a predetermined path over the breast of the heel to form a heel cover receiving slot in said breast, and means to adjust the cutter heightwise and widthwise of the breast of the heel so presented properly to locate the cutter to start the slot.

110. In a machine for slotting heels, a heel carrier comprising an abutment for engaging the attaching face of a heel, a pin extending from the abutment and shaped to enter a recess in the attaching face of the heel, a bar for engaging the lip of the heel to orient the same about the pin, and a member to clamp the oriented heel against the abutment.

111. In a heel slotting machine, a turret, a plurality of heel carriers mounted upon the turret, each of the carriers comprising an abutment for engaging the attaching face of a heel, a pin extending from the abutment and shaped to enter a recess in the attaching face of the heel, a bar for engaging the lip of the heel to orient the same

about the pin, and a member to clamp the oriented heel against the abutment.

112. A machine for operating upon heels having, in combination, cutting units to form slots in heels, a turret upon which the heels are mounted and presented successively to the cutting units, mechanism to index the turret, mechanism to lock the turret when the heels are in position to be operated upon, and mechanism for constraining the turret to move in timed relation with the cutting units.

113. A slotting machine having, in combination, a rotary cutter and a heel clamp relatively movable one past the other in a curved path the curvature of which is constrained to planes substantially parallel to the axis about which the cutter rotates.

114. A slotting machine having, in combination, a rotary cutter, a support for a heel, and means to effect relative swinging movement of the cutter and the support in planes which are disposed substantially parallel to the axis about which the cutter is rotated thereby to form in the breast of the heel a cover receiving slot which deviates laterally.

115. A slotting machine having, in combination, a rotary cutter, a support for a heel, and

means to swing the cutter past the support about an axis in a path the plane of which is disposed at substantially right angles to said axis thereby to form in the heel a cover receiving slot which deviates laterally.

116. A slotting machine having, in combination, a rotary cutter, and a support for a heel, said cutter being mounted for pivotal movement past the support in a plane which is disposed in substantially parallel relation to the axis of rotation of the cutter about an axis which passes substantially through the center of curvature of a breast edge of the heel thereby to form in the breast of the heel a cover receiving slot which extends substantially parallel to said breast edge.

117. A slotting machine having, in combination, a slot-forming member, a Louis heel-supporting member, and means for producing relative movement of the slot-forming member and the heel-supporting member in three directions thereby to form in the breast of the heel a laterally curved cover receiving slot which extends heightwise of the heel and is located alongside a breast edge thereof.

LEWIS J. BAZZONI. 100
